UNITED STATES PATENT OFFICE.

FRANK MELVIN MORTON, OF PHOENIX, ALABAMA.

BEAM-SUPPORTING ATTACHMENT FOR WARP-FRAMES.

1,010,298.

Specification of Letters Patent. Patented Nov. 28, 1911.

Application filed November 23, 1910. Serial No. 593,843.

To all whom it may concern:

Be it known that I, FRANK M. MORTON, a citizen of the United States, residing at Phoenix city, in the county of Lee and 5 State of Alabama, have invented certain new and useful Improvements in Beam-Supporting Attachments for Warp-Frames; and I do declare the following to be a full, clear, and exact description of the invention, 10 such as will enable others skilled in the art to which it appertains to make and use the same.

This invention relates to improvements in beam supporting attachments for warp 15 frames.

One object of the invention is to provide an improved means for revolvably supporting a beam on the warp frame whereby the beam may be readily engaged with and re- 20 moved from the supporting mechanism.

With this and other objects in view, the invention consists of certain novel features of construction, combination and arrangement of parts as will be more fully described 25 and particularly pointed out in the appended claim.

In the accompanying drawings: Figure 1 is a perspective view of a portion of a warp frame showing the application of the 30 invention thereto; Fig. 2 is a top plan view of the same; Fig. 3 is a vertical longitudinal section through the supporting attachment showing in dotted lines a beam applied thereto; Fig. 4 is a front view of the driv- 35 ing and supporting socket with which one end of the beam shaft is operatively engaged; Fig. 5 is a rear view thereof; Fig. 6 is a vertical cross sectional view of the same on the line 6—6 of Fig. 4.

40 Referring more particularly to the drawings, 1 and 2 denote the opposite standards of the warp frame connected together by longitudinal bars 3 and having in their upper edges bearing notches 4 which form no part of the present invention. Secured 45

to the outer side of the standard 1 and projecting laterally therefrom, is a bearing bracket 5 provided with an attaching plate 6 which is bolted or otherwise rigidly se- 50 cured to the standard 1 as shown. On the outer end of the bracket 5 is formed a bearing box 7 having therein a longitudinally disposed cylindrical bearing passage. On the lower side of the box 7 is formed an 55 apertured lug 8 which is bolted or otherwise secured to the upper end of a support-

ing standard 9 on the lower end of which is formed a lug whereby said standard is secured to the floor or other support.

With the bearing box 7 is revolvably en- 60 gaged the cylindrical stem or shaft 10 of a journal receiving socket 11 adapted to receive the journal of the adjacent end of the beam 12 as shown in dotted lines in Fig. 3 of the drawing. The socket 11 is formed in upper and lower sections which are connected at one side by a hinge 13 and at their opposite sides are secured together by a bolt or screw 14 having a flattened ap- 65 pertured lower end pivotally mounted on a bolt or rivet 15 arranged in a pair of apertured ears or lugs 16 formed on the outer side of the lower section of the socket as shown. The upper end of the bolt or screw 14 is adapted to be swung into a notch or recess 70 17 formed between two laterally projecting lugs 18 formed on this side of the upper section of the socket immediately above the apertured ears 16 on the lower section. On the threaded upper end of the bolt or screw 75 14 is a clamping nut 19 the lower end of which, when the nut is screwed down on the bolt, will engage the upper sides of the lugs 18 and thereby securely fasten the upper section down into operative engage- 80 ment with the lower section to form the socket with which the journal of the beam is engaged as hereinbefore described.

On the inner end of the lower section of 85 the socket is formed a crank arm 20 pro- 90 vided with a threaded opening 21 in which is mounted a crank pin 22 which may be inserted into an aperture 23 in the adjacent end or head of the beam, thereby locking the beam into engagement with the socket. 95 On the projecting outer end of the shaft 10 is adapted to be secured a driving gear or pulley 24 by means of which power is applied to the shaft 10 and socket 11 for re- 100 volving the same and the beam secured thereto.

Bolted or otherwise secured to the oppo- 105 site standard 2 of the warp frame is a bearing bar or bracket 25 having formed in its outer end a vertically disposed bearing notch 26 in which is arranged a bushing 27 with which may be revolvably engaged the journal on this end of the beam whereby said end is revolvably supported. Arranged in the outer end of the bar or bracket 25 is 110 a thumb screw 28 which is adapted to be screwed into engagement with the bushing

arranged in the notch 26 of the bearing bar 25 whereby said socket and the journal on this end of the beam is removably and revolvably secured to the warp frame. By 5 thus supporting the beam it will be seen that the same may be readily engaged with and revolvably supported in proper position on the warp frame and may be readily removed therefrom when desired.

10 From the foregoing description taken in connection with the accompanying drawings, the construction and operation of the invention will be readily understood without requiring a more extended explanation.

15 Various changes in the form, proportion and the minor details of construction may be resorted to without departing from the principle or sacrificing any of the advantages of the invention as defined in the appended claim.

Having thus described my invention what I claim is:

20 In the device of the character described, a

warp frame comprising parallel standards, one of said standards being provided with 25 a bearing for one spindle of a warp beam projecting beyond its front edge, a horizontal bracket secured to the outside of the other standard and projecting beyond its front edge, a bearing block carried by said bracket in line with the first named bearing and provided with an independent supporting standard, and a driving and supporting socket member comprising a shaft journaled in the bearing block, a socket for receiving 30 the beam spindle and a crank arm carrying a crank pin adapted to engage an eccentrically located opening in the head of the warp beam.

In testimony whereof I have hereunto set 40 my hand in presence of two subscribing witnesses.

FRANK MELUIN MORTON.
